(57) **CLAIM**

The ornamental design for an adapter for changing LED light bulbs, as shown and described.

DESCRIPTION

FIG. 1 is a perspective view of an adapter for changing LED light bulbs showing our new design, it being understood that the adapter is radically symmetrical;

FIG. 2 is a top view of the adapter;

FIG. 3 is a bottom view of the adapter;

FIG. 4 is a side view of the adapter from one angular orientation; and,

FIG. 5 is a side view of the adapter from another angular orientation.
